UNITED STATES PATENT OFFICE.

HERMAN URBAHNS, OF HAMMOND, INDIANA.

CAR-SEAL.

1,177,834.

Specification of Letters Patent.

Patented Apr. 4, 1916.

Application filed November 22, 1913, Serial No. 802,459. Renewed September 20, 1915. Serial No. 51,699.

To all whom it may concern:

Be it known that I, HERMAN URBAHNS, citizen of the United States, residing at Hammond, in the county of Lake and State 5 of Indiana, have invented certain new and useful Improvements in Car-Seals, of which the following is a specification, reference being had to the accompanying drawings.

This invention relates to improvements 10 in car seals and has for its principal object to provide a device of this character which is simple in construction, durable and reliable in operation and may be easily and quickly manipulated and applied to a car 15 door to prevent the undetected opening thereof.

My invention has for another object to provide a device of this character which will obviate the necessity of employing a sealing 20 iron or other tool to effect the application thereof.

The invention has for another and very important object the provision of a car seal which is constructed from a single piece of 25 material thereby conducing to a low cost of manufacture and resulting in a construction of a highly desirable and superior nature.

With the above and other objects in view 30 as will become apparent as the description proceeds, the invention consists in certain constructions, combinations and arrangements of the parts that I shall hereinafter fully describe and claim.

For a full understanding of the invention, reference is to be had to the following 35 description and accompanying drawing, in which—

Figure 1 is a plan view of the seal in 40 blank or as it is cut from the metal sheet. Fig. 2 is a perspective view illustrating the arrangement of the several structural features of the metal strip, at a point in the folding of the strip for its application to 45 a door or other part to be sealed, one of the flanges on the edge of the strip being partially broken away. Fig. 3 is a similar view, the seal being completely folded and shown applied to a car door; Fig. 4 is an 50 enlarged longitudinal section taken on the line 4—4 of Fig. 3; Fig. 5 is a section taken on the line 5—5 of Fig. 4.

Referring in detail to the drawing, 5 55 designates the body strip of the seal which is cut from a sheet of tin or other metal. This metal strip adjacent one of its ends

is wider than the remaining portion of the strip, thereby producing flanges 6 upon its longitudinal edges. The adjacent end of the strip constitutes a tongue 7. The 60 widened portion of the strip has centrally formed therein a depression or recess 8 which is produced by means of a suitable die. The body 5 of the strip adjacent to the flanges 6 is further formed with a protuberance or projection 9 projecting from one face thereof in an opposite direction to the bulged or outwardly struck portion of the strip which forms the socket or recess 8. A longitudinally extending tongue 10 is cut 70 from the strip at its other end, one end of said tongue remaining integrally attached to the strip while the point of said tongue projects inwardly. This tongue normally lies in the plane of the body 5. 75

In the application of my invention to a car door, the metal strip 5 is first bent upon itself at the inner ends of the flanges 6 thereon so as to dispose the recess 8 in opposed relation to the spur or projection 9 on the 80 strip. The flanges 6 on the edges of said strip are now bent over upon the body of the strip as shown in Fig. 5 and crimped thereon to retain the end portion of the strip which is provided with the tongue 7 and recess 8 in its folded position with relation to the body of the strip. The tongue 7 is now bent at its point of connection to the widened portion of the strip so that the same is disposed between said spur or projection and 85 the recess. The body portion 5 of the strip is bent and the end thereof which is provided with the tongue 10 extended through the staple on the door. This end of the strip is now inserted between the tongue 7 and the projection 9, and pressure is brought to bear upon the widened portion of the strip so that the projection 9 will act to force the tongue 10 out of the plane of the body of 90 said strip. When the attempt is made to withdraw the end of the strip from between the flanged portion thereof and the body of the strip, the tongue 10 will move over the end of the tongue 7 so that said latter tongue will force the tongue 10 outwardly from 95 the body of the strip and into the depression or recess 8. This tongue will effectually prevent the withdrawal of the end of the metal strip, by its interlocking engagement with the tongue 7. 100

From the above description taken in connection with the accompanying drawing, it is 110

believed that the construction and manner of operation of my invention will be clearly and fully understood.

As the device may be cut or stamped out of a single sheet of metal, it will be obvious that the same can be produced at very small manufacturing cost. It can also be very easily and quickly manipulated and applied to a car door or other part which it is desired to seal.

The locking action is automatic and the device as a whole highly serviceable and convenient in practical use.

While I have above described the preferred form and construction of the several features of my invention, it will be understood that the device in these particulars is susceptible of considerable modification and I therefore reserve the privilege of resorting to all such legitimate changes as may be fairly embodied within the spirit and scope of the invention as claimed.

Having thus described the invention, what is claimed is:

25. The herein described car seal formed from a ductile metal strip, said strip being provided adjacent one of its ends and on its longitudinal edges with flanges, the end of said strip extending beyond the flanges constituting a tongue, said strip being provided centrally between the flanges thereon with an outwardly struck portion forming a rela-

tively narrow longitudinally extending seat or recess, said strip also having a projection formed thereon inwardly of and in spaced relation to the inner ends of said flanges, a tongue cut from said strip adjacent its other end and normally lying in the plane of the body of the strip, said flanged portion of the strip being adapted to be folded over upon the strip body to dispose said recess in opposed relation to said projection, said first named tongue being folded inwardly longitudinally of the strip to extend over one end of said recess, said flanges being adapted to be bent around the edges of the strip to retain the recessed portion thereof in folded relation to the strip body, and the other end of said strip being adapted for insertion between said folded tongue and the projection on the strip body whereby the second named tongue is forced out of the plane of the strip and into said recess to dispose the same in position for interlocking engagement with said first named tongue upon an attempt to withdraw the last referred to end of the strip.

In testimony whereof I hereunto affix my signature in the presence of two witnesses.

HERMAN URBAHNS.
